SHOE SOLE FORMER

William H. Doherty, Elmhurst, N. Y.

Application February 1, 1949, Serial No. 73,883

10 Claims. (Cl. 18—34)

1

This invention relates to new and useful improvements in a device for forming plastic or composition soles on shoes and has especial reference to a novel form of mold therefor.

An object of the invention is to provide a mold device which can be quickly and easily attached to and removed from the shoe, and which is composed of a few simple parts, and is economical and efficient to operate.

A further object is to provide a mold which can be readily adapted to be associated accurately with any shape of shoe to form a mold for any shape or size of sole, and which requires no particular professional skill in its operation.

Further and more specific objects, features, and advantages will more clearly appear from a consideration of the detailed specification hereinafter set forth especially when taken in connection with the accompanying drawings which illustrate a present preferred form which the invention may assume and which form part of the specification.

In brief and general terms, the invention concerns the provision of flexible mold-bands around the sides of the welt of a shoe to which a sole is to be attached in any suitable manner. These bands fit snugly around the welt and extend along their bottom edge below said welt to form therewith a mold cavity into which the material forming the sole is disposed. This material may be fluid or viscous and is later treated in any desired manner to connect it with the inner sole and welt. At the sides of the shoe intermediate its length, are disposed gripping means which are adjustable to engage the sides of the shoe at the welt level and aid in clamping the mold-bands in position. The vertical level of the bottom edge of the mold-band is determined by a plurality of clips, which engage the bottom edge of the band and are disposed along the welt and held in this position by a flexible element such as a wire, which is adjustably related to the shoe either by being connected to the shoe gripping means or by other suitable means.

The present preferred forms which the invention may assume are shown in the drawings, of which:

Fig. 1 is an inverted plan view of the mold inside the shoe;

Fig. 2 is a side elevation thereof in upright position;

Fig. 3 is a cross section taken on the line 3—3 of Fig. 2;

Fig. 4 is an inverted plan view of a modified form of the mold;

2

Fig. 5 is a side elevation of the modified form in upright position;

Fig. 6 is a cross section taken on the line 6—6 of Fig. 5;

Fig. 7 is a perspective view of a wire guiding clip; and

Fig. 8 is a partial sectional view through the shoe showing a modified form of clip for holding the mold-band in place.

Referring now merely to the specific forms of the invention shown in the drawings, it is to be noted with respect to Figures 1, 2 and 3 which show the preferred form, that the purpose of this invention is to enable a plastic or composition sole to be readily applied to a shoe, of which the upper 10 and the inner sole and welt portion 11 are clearly shown. A shoe tree or last 12 of any suitable type is inserted in the shoe to hold it firmly in proper shape.

As shown in the drawings, a mold-band 13 is disposed around the edges of the welt 11 as particularly seen in Figure 3, with a major portion of the band extending below the welt to form a mold cavity with the welt and the inner sole into which plastic material, either in viscous or fluid form, may be disposed and then by suitable treatment, can be allowed to set into proper shape in firm association with the inner sole and welt 11.

In the form shown in Figures 1, 2 and 3, the band is comprised of two pieces which are connected at adjacent ends by a rivet 14 and are disconnected at their other adjacent ends. This band is disposed around the welt and is engaged at the sides of the shoe by gripping members or supporting blocks 15. These blocks are connected at their top by frame members 16 extending across the top of the shoe and at the bottom, are connected by a bar 17 having a screw 18 at one end to be operated to pull the blocks 15 together against the sides of the shoe. The adjusting bar 17 is pivoted on a bracket 19 at one end and passes through a bracket 20 at the other, the brackets being connected respectively to the blocks 15.

In order to determine the vertical level of the bottom edge of the mold-band 13, I provide a series of clips 21 which have upper portions resting on the welt and lower portions bent under the lower band 13. These clips 21 are held on the welt by means of a flexible element or wire 22, as shown in the first three figures. This wire at one end is connected to a band 23 preferably of metal, passing around the heel portion of the shoe, the other end of this band being

connected to one of the blocks 15. The wire passes through apertures in the blocks 15 and at the free end, is connected to a handle portion 24, whereby the operator may pull on the wire to tighten its engagement with the clips. This wire 22 extends along around the shoe just above the welt. A set screw 25 on one of the blocks 15 can be adjusted to clamp the free end of the wire in any adjusted position.

The inner faces of the blocks 15 are curved as shown at 26, to conform to the shape of the shoe at the intermediate side portions thereof. Curved levers 27 are pivoted on the blocks in suitable slots therein and adapted to be moved into engagement with the mold-band to press these portions of the bands against the shoe. Set screws 28 enable these levers to be held in adjusted position. A filler block 29 of two pieces, is separated by a spring 30 and suitably formed may be disposed against the inner sole between the blocks 15 in case it is desired to mold the front portion of the sole and the heel separately. These filler plates may also be put in after the sole is formed for the purpose of building up the heel and separating the sole portion from the heel portion.

As shown in the first three figures, the blocks 15 are provided with slotted brackets 31 through which certain free portions of the mold-band may extend in a rather tight fitting manner.

In the operation of this form of the device, the blocks 15 are disposed adjacent the side of the shoe with the band 13 disposed around the welt and held in vertical disposition by the clips 21. The blocks are held tightly in position against the shoe to clamp the band by tightening up on the screw 18, then the handle on the wire 22 is pulled to tighten the wire around the welt and the set screw 25 is then tightened up to hold the wire in this position. The material is then placed in the mold in any suitable manner and treated to connect it to the sole and welt in any desired manner. The filler plates 29 may or may not be used depending upon the particular requirements at the moment. It is obvious that it is a relatively simple matter to attach this mold device and to remove it.

In the forms shown in Figures 4 to 8, we have the same general construction except that instead of the blocks 15, we now have posts 32 extending up alongside of the shoe and adjustable by means of slotted bracket plates 33 to press against the shoe and hold the band 13 in position. In this case as before, the band at one portion is connected to the post and the other ends are free. In this case, the band also extends around the heel as well as the sole portion. The wire 22 in this form, is also provided but is connected somewhat differently, in that its free ends are connected to metal plates 34, which are connected around the back of the shoe by an elastic band 35 which extends around the back of the heel and the back of the upper in the manner shown, and exerts a constant pull on the wire. The wire 22, as before, passes through openings in plates 36 connected to the upper end of the post 32. The bands on each side thereof intermediate the length of the shoe, are provided with adjustable guide plates 37 pivoted to the bands but rather tightly so and provided with an offset portion 38 having spaced grooves 39 therein, to receive the wire and hold it in a spaced relation with respect to the post 32 and the welt.

In this form also, the clips employed, may be of the form shown in Figure 8, in which the upper

end is slotted as at 40 and is bent reversely on itself extending through said slot and having a hooked end 41 to engage the wire 22.

It is perfectly obvious that in either form of the invention shown, the mold device and its related parts can be adapted to the shoe very quickly and easily and form a practical, efficient mold.

While the invention has been described in detail and with respect to the preferred form shown in the drawings, it is not to be limited to such details and forms since many changes and modifications may be made in the invention without departing from the spirit and scope of the invention in its broadest aspects. Hence, it is intended to cover any and all forms and modifications of the invention which may come within the language or scope of any one or more of the appended claims.

What I claim as my invention, is:

20 1. In a mold apparatus for forming soles on shoes having a connected upper and welt the improvement which includes adjustable means to grip the sides of the shoe, a flexible mold band adapted to extend along and below the sides of 25 the welt to form a mold cavity therewith, and clamping means on the shoe gripping means, said band being located between the welt and the shoe gripping means and said clamping means adapted to position snugly the mold band 30 against the sides of the welt.

2. In a mold apparatus for forming soles on shoes having a connected upper and welt the improvement which includes supports adjustable at the sides of the shoe to grip the same along the 35 line of the welt, a flexible mold-band adapted to extend along the sides of the welt and below the same to form a mold cavity therewith, clips adapted to extend along the welt engaging the bottom of the band to hold it in a vertical relation 40 to the welt, and a flexible element engaging the clips to hold them in position said connector adapted to extend along the upper edge of the welt and adjustably connected to said supports.

3. In a mold apparatus for forming soles on 45 shoes having a connected upper and welt the improvement which includes, a mold-band adapted to extend around the welt and below the same, clips to support the bottom edge of the band, and a flexible element adapted to extend around the 50 welt and engaging said clips to hold them in position with respect to the band and the welt.

4. In a mold apparatus for forming soles on 55 shoes having a connected upper and welt the improvement which includes, a mold band adapted to extend around the welt and below the same, blocks adjustable against the sides of the welt to hold the band tightly in position, levers on said blocks to clamp against the band, a wire adapted to extend around the welt and adjustably connected to said blocks, and clips engaging the bottom 60 of the band and supported by said wire.

5. In a mold apparatus for forming soles on 65 shoes having a connected upper and welt the improvement which includes, a mold band adapted to extend around the welt and below the same, clips engaging the bottom of the band to hold it in position, and a wire adapted to extend around the welt and supporting said clips.

6. In a mold apparatus for forming soles on 70 shoes having a connected upper and welt the improvement which includes, a mold-band adapted to extend around the welt and below the same, forming blocks adjustable against the sides of the shoe to hold the band thereagainst, means connecting the blocks to adjust their pressure

against the sides of the shoe, and levers on the blocks adjustable against the band at the sides of the welt.

7. In a mold apparatus for forming soles on shoes having a connected upper and welt the improvement which includes a mold-band adapted to extend around the welt and below the same, forming blocks adjustable against the sides of the shoe to hold the band thereagainst, means connecting the blocks to adjust their pressure against the sides of the shoe, levers on the blocks adjustable against the band at the sides of the welt, a metal band adapted to extend around the rear portion of the shoe, a wire connector connected to the metal band adjustable on the blocks and adapted to extend around the shoe along the top of the welt, and clips supported by said wire and engaging the bottom of the band at spaced points to maintain the level of the lower edge of the band.

8. In a mold apparatus for forming soles on shoes having a connected upper and welt the improvement which includes a mold-band adapted to extend around the welt and below the same, forming blocks adjustable against the sides of the shoe to hold the band thereagainst, means connecting the blocks to adjust their pressure against the sides of the shoe, curved levers pivoted on the blocks and adjustable against the band at the sides of the welt, a wire connector adjustable on the blocks and adapted to extend around the shoe along the top of the front of the welt, clips supported by said wire and engaging the bottom of the band at spaced points to maintain the level of the lower edge of the band, a metal strip adapted to extend around the heel portion of the shoe and connected to one end of said wire, the other end of the strip connected to one of said blocks, the other end of the wire extending through said last mentioned block, and means on said block to clamp said wire in adjusted condition thereon.

9. In a mold apparatus for forming soles on shoes having a connected upper and welt the

improvement which includes a mold-band adapted to extend around the welt and with its bottom edge below the same, sole gripping posts adapted to be adjustably disposed on the opposite sides of the welt, means for adjusting said posts against the welt, clips adapted to extend around the welt and engaging the bottom of the band, a flexible connector engaging the clips and supported on said posts, an elastic device adapted to pass around the back of the heel and the shoe, the ends of said connector being joined to the elastic device and exerting tension thereon.

10. In a mold apparatus for forming soles on shoes having a connected upper and welt the improvement which includes a mold-band adapted to extend around the welt and with its bottom edge below the same, sole gripping posts adapted to be adjustably disposed on the opposite sides of the welt, means for adjusting said posts against the welt, clips adapted to extend around the welt and engaging the bottom of the band, a flexible connector engaging the clips and supported on said posts, an elastic device adapted to pass around the back of the heel and the shoe, the ends of said connector being joined to the elastic device and exerting tension thereon, and a connector guide plate pivoted to the band on opposite sides thereof adjacent the posts and having a series of grooves therein to selectively guide the wire passing therethrough.
